CLAIM

The ornamental design for an abrasive disc with a distribution of holes, as shown and described.

DESCRIPTION

FIG. 1 is a perspective view of an abrasive disc according to the present design;

FIG. 2 is a front view of the abrasive disc of FIG. 1;

FIG. 3 is a back view of the abrasive disc of FIG. 1; and,

FIG. 4 is a side view of the abrasive disc of FIG. 1.
